UNITED STATES PATENT OFFICE.

JOHN SMITH, OF HOPEDALE, MASSACHUSETTS, ASSIGNOR TO DRAPER COMPANY, OF HOPEDALE, MASSACHUSETTS, A CORPORATION OF MAINE.

AUTOMATICALLY-THREADING SHUTTLE.

1,074,656.

Specification of Letters Patent.

Patented Oct. 7, 1913.

Application filed April 5, 1913. Serial No. 759,037.

To all whom it may concern:

Be it known that I, JOHN SMITH, of Hopedale, in the county of Worcester and State of Massachusetts, have invented a new 5 and useful Improvement in Automatically- Threading Shuttles, of which the following is a specification.

The present invention is an improvement upon the automatically threading shuttle set 10 forth in United States Letters Patent of Stimpson, No. 933,497, September 7, 1909, and the object of the improvement is to still further insure the maintenance of the thread in proper position after the shuttle has been 15 automatically threaded.

The present improvement is illustrated in the accompanying drawings wherein—

Figure 1 is a plan view of the eye end of the shuttle containing the present improvement. Fig. 2 is a horizontal section thereof in the plane indicated by the line 2—2 in Fig. 3. Fig. 3 is a side view. Fig. 4 is a cross section in the plane indicated by the line 4—4 in Fig. 1. Fig. 5 is a side view of 25 the threading device detached from the shuttle, parts being broken away to show the construction. Fig. 6 is a perspective view of the structure which constitutes the present addition to the shuttle. Fig. 7 is a perspective view of the slotted lining of the 30 shuttle eye.

Except for the structure which is illustrated in the detached Fig. 6 and elsewhere in the drawings the remainder of the illustrated shuttle is similar to what is shown in the said Stimpson Patent No. 933,497. As in that patent, A is the shuttle having the bobbin chamber B and a slotted thread eye C. A sheet metal automatic threader is employed which is bent into proper shape to constitute the front side wall D, the rear side wall E, and the bottom F of a longitudinal thread passage through which the thread passes on its way from the bobbin 40 chamber B to the slotted eye C. As in said patent, this threading device has a laterally and rearwardly extending beak G under which the thread passes on its way to the slotted eye and there is a forwardly extending 45 overhanging guard H above the beak at the outer end of the thread passage and a laterally and rearwardly projecting guard I at the entrance to the thread passage between the walls D and E for the purpose of 50 maintaining the thread in place. At the 55 thread entrance the bottom F of the threader is bent upwardly and outwardly to form a shoulder J to aid in retaining a tension or friction pad N in place in contact with which the thread runs. The threader is 60 maintained in place in the shuttle by a transverse bolt K. The eye of the shuttle has a slotted metallic lining L. In all of these respects the illustrated shuttle is similar to that of said Stimpson Patent No. 933,497. 65 As shown in that patent there is a long uncovered space within the threader between the two guards H and I, and it sometimes happens that a loop forms in the thread within this space due probably to the shock 70 incident to the abrupt stoppage of the shuttle in its flights and this sometimes results in unthreading the eye or in breaking the thread. The primary object of the present invention is to introduce an additional 75 thread retainer within the thread passage and between the two guards and sufficiently close to the normal path of the thread to prevent the looping of the thread and its escape from the threader. To this end a 80 metallic block M is provided which is inserted within the longitudinal thread passage of the threader and rests on the bottom thereof. This block M has a transverse aperture a, through which the bolt K passes 85 thus holding the block securely in place. This block is formed with a thread retainer b which overhangs a thread groove c whose axis is in line with the longitudinal thread passage within the threader. The thread retainer b extends from the front wall of the 90 thread passage rearwardly and downwardly toward the rear wall E of the threader stopping short of said rear wall so as to leave just room for the downward passage of the 95 thread. The downturned edge of the retainer b approaches close to the body of the block M leaving a narrow slot g for the entrance of the thread into the groove c. The bottom of the groove c is below the bottom 100 of the slot g, and below the upper portion of the shuttle eye. The upper surface of the retainer b is downwardly inclined so as to direct the thread to the thread slot g. The thread groove c communicates with the 105 thread eye C through a notch d in the wall of the block M and this notch d has a downwardly extending thread directing surface e

at the forward face of the block which facilitates the passage of the thread into the eye C.

The rear end *f* of the block M is downwardly and outwardly inclined so as to form with the upwardly and outwardly inclined shoulder J of the threader a chamber for the tension pad N which is wider at the bottom than at the top thus securely retaining the 10 pad N in place.

I claim—

1. An automatically threading shuttle having, in combination, a slotted thread eye; a sheet metal threader having a longitudinal thread passage communicating at its outer end with said eye, a laterally extending beak partly crossing said thread passage, and laterally extending thread guards at opposite ends of said passage; and a thread block located within and at the bottom of said passage, said block having (a) a longitudinal thread groove open at both ends with its outer end opposite the shuttle eye and its bottom below the upper portion of the shuttle eye, (b) a thread retainer on its front side extending downwardly and rearwardly toward the rear wall of the thread passage but stopping short thereof to leave a narrow throat for the thread, said retainer being located between the thread guards, (c) a narrow slot below the bottom edge of said retainer and communicating with said thread groove, and (d) an inwardly extending notch on its front side opposite the shuttle eye through which the thread extends from the thread groove to the shuttle eye, said notch having a downwardly and outwardly extending thread directing surface.

2. An automatically threading shuttle having, in combination, a slotted thread eye; a sheet metal threader having a longitudinal thread passage communicating at its outer end with said eye, a laterally extending beak partly crossing said thread passage, and laterally extending thread guards at opposite ends of said passage; and a thread block located within and at the bottom of said passage, said block having a longitudinal thread groove open at both ends with its outer end opposite the shuttle eye and its bottom below the upper portion of the shuttle eye, a thread retainer on its front side extending downwardly and rearwardly toward the rear wall of the thread passage but stopping short thereof to leave a narrow throat for the thread, said retainer being located between the thread guards, and a narrow slot below the bottom edge of said retainer and communicating with said thread groove.

60 3. An automatically threading shuttle having, in combination, a slotted thread eye; a threader having a longitudinal thread pas-

sage communicating at its outer end with said eye, a laterally extending beak partly crossing said thread passage, and laterally 65 extending thread guards at opposite ends of said passage; a thread retainer extending from the front wall of the thread passage downwardly and rearwardly toward the rear wall of the thread passage, but stopping short thereof to leave a narrow throat for the thread, said retainer being between the thread guards; a thread groove below the retainer; a narrow slot below the bottom edge of said retainer and communicating 75 with said thread groove; and an inwardly extending notch at the front side of said groove and opposite the shuttle eye through which the thread extends from the thread groove to the shuttle eye. 80

4. An automatically threading shuttle having, in combination, a slotted thread eye; a threader having a longitudinal thread passage communicating at its outer end with said eye, a rearwardly and laterally extending beak partly crossing said thread passage, and laterally extending thread guards at opposite ends of said passage; and a thread retainer extending partly across the thread passage but leaving a narrow throat 90 for the thread, said retainer being between the beak and the inner thread guard at the entrance to the thread passage.

5. An automatically threading shuttle having, in combination, a slotted thread eye; 95 a sheet metal threader having a longitudinal thread passage communicating at its outer end with said eye, and an upturned outwardly inclined shoulder at the entrance to said passage; a block at the bottom of said 100 passage having at its inner end an outwardly and downwardly inclined face; a tension pad between said shoulder and the inner end of said block; and a transverse bolt in the shuttle passing through said 105 threader and said block.

6. An automatically threading shuttle having, in combination, a slotted thread eye; a threader having a longitudinal thread passage communicating at its outer end with 110 said eye, and an upwardly extending and outwardly inclined shoulder at the entrance to said passage; a block at the bottom of said passage having at its inner end an outwardly and downwardly inclined face; and 115 a tension pad between said shoulder and the inner end of said block.

In witness whereof, I have hereunto signed my name in the presence of two subscribing witnesses.

JOHN SMITH.
